UNITED STATES PATENT OFFICE.

ROBERT M. KLIEMANT, OF BALTIMORE, MARYLAND.

GAME.

1,325,201.

Specification of Letters Patent.

Patented Dec. 16, 1919.

Application filed May 2, 1919. Serial No. 294,212.

To all whom it may concern:

Be it known that I, ROBERT M. KLIEMANT, a citizen of the United States, residing at Baltimore, in the State of Maryland, have 5 invented certain new and useful Improvements in Games, of which the following is a specification.

This invention relates to improvements in games, and has for its object to provide a 10 simple, cheap and efficient game for amusement of young and old.

The invention consists of the novel construction and arrangement of the parts hereinafter more fully set forth in the following 15 specification and pointed out in detail in the appended claims.

In the accompanying drawing,—

Figure 1 is a front elevation of my invention.

20 Fig. 2 is a vertical section of Fig. 1 on the line 3—3.

Fig. 3 is a detail view of the rod on which the movable figure is mounted.

Referring to the accompanying drawing, 25 forming part of this specification, and in which like reference numerals designate like parts throughout the several views, thereof 1 designates a base having vertical end pieces 2 at each end and a vertical back 30 3. Each of said end pieces 2 is provided with an aperture 4 and one is provided with the word "No" and the other with the word "Yes." The rod 5 is provided with a loop

6 at each end and projects through the apertures 4 in said end pieces and has mounted 35 thereon a movable figure 7.

When operating the game the rod 5 is held at each end by the loops 6 with the lower end of the figure 7 just touching the base 1 and the vibration of the rod 5 caused 40 by the nervousness of the hand results in causing the figure 7 to be moved up and down against the base 1 which results in the said figure 7 moving along said rod 5 toward the word "Yes" or "No" presumably 45 in answer to a question asked by the operator of the game.

While I have shown and described the movable figure 7 mounted on a rod, the said figure may be operated on a cord held taut. 50

Having thus described my invention, what I claim is:

1. A game comprising a base having two end pieces each provided with an aperture, a rod projecting through said aperture, a 55 figure movably mounted on said rod between said end pieces.

2. A game comprising a base, two upright end pieces each provided with an aperture therein, a rod projecting through said apertures and having a loop at each end, and a movable figure mounted on said rod between said end pieces. 60

In testimony whereof I affix my signature.

ROBERT M. KLIEMANT.
